COMBINED ENGINE SHROUD AND BLADE HOUSING FOR A LAWN MOWER

Ross E. Cornwell, Chicago, Ill., assignor to Sunbeam
Corporation, Chicago, Ill., a corporation of Illinois

Filed June 15, 1960, Ser. No. 60,975

Term of patent 14 years

(Cl. D40—1)

FIG. 1.

FIG. 2.

Fig. 3.

Fig. 4.

FIG. 1 is a front perspective view of a combined engine shroud and blade housing for a lawn mower embodying my new design;

FIG. 2 is a left side elevational view thereof;

FIG. 3 is a top plan view thereof; and

FIG. 4 is a rear elevational view thereof.

The dominant features of my design reside in the portions shown in full lines.

I claim:

The ornamental design for a combined engine shroud and blade housing for a lawn mower, as shown and described.
